UNITED STATES PATENT OFFICE.

PETER CHRISTMAN, OF GREEN BAY, WISCONSIN.

MECHANICAL MOVEMENT.

1,004,147.

Specification of Letters Patent. Patented Sept. 26, 1911.

Application filed June 27, 1910. Serial No. 569,153.

To all whom it may concern:

Be it known that I, PETER CHRISTMAN, a citizen of the United States, residing at Green Bay, in the county of Brown and State of Wisconsin, have invented certain new and useful Improvements in Mechanical Movements; and I do declare the following to be a full, clear, and exact description of the invention, such as will enable others skilled in the art to which it appertains to make and use the same.

This invention relates to a mechanical movement and has for its object to provide mechanism for converting a reciprocating movement into a rotary movement or vice versa and at the same time to so construct and arrange the several parts of the mechanism that they will mutually support and brace each other at all times.

20 The movement is applicable to all kinds of machinery having a forward and backward movement such as pump pistons, engines, lathes and the like or it may be used in any place where a crank has formerly been employed.

With these and other objects in view, the invention consists of certain novel features of construction, combination and arrangement of parts as will be more fully described 30 and particularly pointed out in the appended claim.

In the accompanying drawings: Figure 1 is a side elevation of this improved movement; Fig. 2 is an end view thereof; Fig. 3 is a 35 side elevation of one of the frame members carrying the stationary guides; Fig. 4 is a horizontal section taken on the line 4—4 of Fig. 1.

In the embodiment illustrated two cross bars or plates A and B for supporting this improved movement form a part of a suitable supporting structure, (not shown) said movement being here shown as applied to a pump rod C. A power shaft 1 is journaled 40 in the cross bars A and B and is provided at one or both ends with a drive wheel or pulley 2. A gear wheel 3 is fixed to the shaft 1 and is driven thereby for imparting motion to an internal oblong gear 4. The 45 side members of this gear 4 are provided on both faces with longitudinally-extending guides preferably in the form of ribs 5 and 5' which are designed to engage stationary guides as 6 and 6' formed on the inner faces 50 of the cross bars or plates A and B of the supporting structure and which are prefer-

ably made in the forms of ribs adapted to engage the ribs 5 and 5'. The ribs 5 and 5' of the oblong gear 4 move on one side of these guides 6 and 6' on the upward movement of gear 4 and on the other side on the downward movement of said gear, whereby said gear is held continuously in mesh with the gear wheel 3. Stationary rods 7 and 8 are spaced laterally apart and mounted in the 60 supporting frame the lower ends thereof being preferably fixed to a block D through which the piston rod C passes and at their upper ends they are fixed to cross rods 13 and 14 arranged on the cross bars A and B 65 respectively and fastened at their ends to the supporting frame (not shown). Similar upright rods 7' and 8' are arranged in longitudinal alinement with the rods 7 and 8 and are fixed at their lower ends to cross 70 rods 15 and 16 arranged on the cross bars A and B above and extending parallel with the rods 13 and 14. The upper ends of these rods 7' and 8' are secured to a fixed member of the supporting structure, (not 75 shown). Crossheads 9 and 10 are movable 80 vertically on the rods 7 and 8 and 7' and 8' respectively and are connected with the upper and lower ends of the internal gear 4 by means of pitmen 11 and 12 which are 85 pivotally connected to the opposite ends of said gear 4 and to the crossheads 9 and 10 respectively. These boxes or crossheads are 90 designed to reciprocate with said internal gear to hold it in an upright position while permitting it to move edgewise. The lower crosshead 9 is connected with the piston rod C to be operated as is clearly shown in Fig. 1. By the arrangement described the elongated internal gear 4 is held at all times in 95 proper mesh with the pinion 3 so that when the shaft 1 is driven said pinion 3 transmits the rotary motion thereof to the gear 4 whereby said gear is reciprocated with the inner faces of the ribs 5' on one side thereof 100 engaging the outer faces of the adjacent stationary ribs 6' and the outer faces of the ribs 5 on the other side of gear 4 engaging the inner faces of the ribs 6, and actuates the pump rod C or other machinery to be 105 driven.

From the foregoing description taken in connection with the accompanying drawings, the construction and operation of the invention will be readily understood without requiring a more extended explanation.

Various changes in the form, proportion

and the minor details of construction may be resorted to without departing from the principle or sacrificing any of the advantages of the invention as defined in the ap-
5 pended claim.

I claim as my invention:—

A mechanical movement comprising a pair of stationary parallel horizontal bars spaced apart, each bar being provided on its inner
10 face with a pair of vertical inwardly projecting ribs opposite similarly constructed and located ribs on the other bar, two pairs of horizontal rods the rods of each pair being in the same vertical plane and secured in
15 and connecting the vertical ribs of each of the stationary horizontal bars, two pairs of vertical rods secured respectively to the upper and lower pairs of the horizontal rods, and projecting upward and downward
20 in alinement with each other, a crosshead

slidably mounted on each pair of vertical rods, an internal oblong gear between the stationary horizontal bars, pitmen connecting the crossheads with the ends of the oblong gear, a horizontal shaft journaled 25 in the stationary bars, a gear secured on the shaft within the oblong gear of a diameter less than the transverse diameter thereof, and vertical ribs projecting laterally on each side of the oblong gear in position to co-act 30 with the ribs of the stationary horizontal bars.

In testimony whereof I have hereunto set my hand in presence of two subscribing witnesses.

PETER CHRISTMAN.
